UNITED STATES PATENT OFFICE.

BENJAMIN C. SMITH, OF BAYONNE, NEW JERSEY, ASSIGNOR TO STANDARD MOTOR CONSTRUCTION COMPANY, OF JERSEY CITY, NEW JERSEY, A CORPORATION OF NEW JERSEY.

INTERNAL-COMBUSTION ENGINE.

Application filed June 3, 1925. Serial No. 34,546.

This invention relates to improvements in internal combustion engines of the so called "high compression" fuel burning "Diesel" type, in which fuel is forced into the engine 5 cylinders and ignited at the proper time when the latter are filled with air under heavy compression. This fuel feed is caused to occur at the proper time and is continued for the desired period to generate the desired 10 power. In such engines the fuel is usually spontaneously ignited, due to the high compression in that particular cylinder into which the fuel is being fed.

One main object of the invention is to 15 provide an engine construction which will guarantee a powerful and efficient starting effort under all conditions for both forward and reverse rotation.

Another object is to provide means which 20 is applicable to any engine of the four-cycle type and especially to those having a plurality of cylinders, and which means will insure positive starting of the engine in either direction in any position of the crank shaft 25 off center.

Other objects will appear to the skilled 30 mechanic from a reading of the following description and an examination of the accompanying drawings, in which—

Fig. 1 is a side elevation of a portion of an 35 engine of the multi-cylinder type, three cylinders being conventionally shown;

Fig. 2 is a relatively enlarged side elevation, partly in section, showing certain 40 details including the compressed air valve;

Fig. 3 is a view taken at right angles to 45 that shown in Fig. 2, showing the engine cylinder in section;

Fig. 4 is an end elevation of the cam shaft 50 with the so called "valve lifters" associated therewith;

Fig. 5 is a side view of the cam shaft 55 shown in Fig. 4;

Fig. 6 is a view similar to Fig. 5, showing 45 said cams rotated one-quarter of a turn;

Figs. 7 to 13 inclusive are diagrammatic 60 views to illustrate the effect of the various cams on the various valve lifters in the various positions of adjustment of the cam shaft, and in these views the cam bumps are illustrated without regard to their relative circumferential position on the shaft;

Figs. 14 to 20 diagrammatically illustrate

respectively the active cam bumps in the various positions of adjustment of the cam 55 shaft as shown in Figs. 7 to 13 respectively, and these views show the relative circumferential position of the said active cam bumps on said shaft.

1 represents the base of an engine. 2—2—2 60 represent cylinders. 3 represents a portion of the crank shaft, the cranks of which are preferably so designed that one crank will always be off center. The several cranks are, of course, connected with the usual pistons 65 by means of the usual connecting rods, the same being too well understood to require illustration. Each cylinder is provided with an atmospheric air intake valve 4, a compressed air inlet valve 5, an exhaust valve 6 and a fuel feed valve 7. All of these valves are preferably mechanically operated by cam bumps on the cam shaft 8, although in some constructions the atmospheric air intake valve 4 may be of the automatic type. In 70 the form shown the cam shaft is adjustable longitudinally to bring the proper bumps in line with their respective valve lifters, so as to cause the valves to function in the manner hereinafter described.

The particular means by which the motion 75 is transmitted from the cam bumps to the valves themselves may be varied at will, but in the particular form shown so called "valve lifters" are provided, the same being mounted to rock on a countershaft 9, said valve lifters being connected by means of suitable rods and rockers which, in turn, engage their respective valves to lift the same from their 80 seats.

In the preferred construction the valve lifters are provided with rollers, which directly engage the cam shaft, thereby reducing friction and wear. Inasmuch as various means for transmitting motion from the cam 85 shaft to the valves are generally well known, and as no invention is claimed for the particular means employed herein, a further description is unnecessary.

10 is a pipe which leads from any suitable 100 source of compressed air supply to the housings for the several compressed air valves, one of which valves is shown in detail in Fig. 2, in which 11 represents a housing for one of the compressed air valves 5. Compressed air enters the housing in the cham- 105

ber directly above the valve 5. The chamber directly below this valve has a passage 12, which communicates with that particular cylinder 2 with which this valve is associated. When the valve 5 is open, compressed air will flow past the same and through the passage 12 into the cylinder to force the piston therein down. In the particular form shown the valve 5 is mounted 10 on a stem which projects upwardly from a piston 14, which latter reciprocates in the housing 11. This piston is also connected by means of a suitable rod 15 with one of the cam-actuated rockers on the countershaft 9.

15 16 is an overbalancing piston mounted on that part of the stem above the valve 5 and positioned in the cylindrical part of the housing adjacent thereto. When the compressed air is on, it is manifest that this 20 overbalancing piston will cause the valve 5 to become seated and normally closed, as shown in Fig. 2.

17 is a throttle valve for the compressed air supply. When the compressed air is 25 turned off the valve 5 may drop by gravity to an open position, so that its rocker will be out of the range of action of its cam bump, thereby avoiding noise and wear. 18 is the check valve between the compressed 30 air valve 5 and the interior of the cylinder 2, the function of which is to prevent any pressure within the cylinder in excess of the compressed air pressure from being forced back into the valve housing 11. The cam 35 shaft 8 is driven from the main shaft 3 in the usual manner, as by gears 19—20, the same being so proportioned that the cam shaft rotates at one-half engine speed, as is customary in four-cycle engines.

40 21 is a manually operable lever suitably connected with the rotatable cam shaft, by which the same may be adjusted endwise for the purpose of engine control.

45 Before describing the operation of the engine, which will be done by referring to the diagrammatic views 7 to 20, I desire to have it understood that in each of said views 22 represents the valve lifter roller for the atmospheric air intake valve 4 of one cylinder, 50 23 represents the lifter roller for the fuel feed valve 7 for one cylinder, 24 represents the lifter roller for the compressed air valve 5 for one cylinder, and 25 represents the lifter roller for the exhaust valve 6 for one cylinder.

55 When the parts stand in the position indicated in Figs. 10 and 17, the rotation of the cam shaft will have no effect on the valve lifters, and consequently the engine is idle. To start the engine ahead or in a forward direction, the cam shaft 8 is shifted longitudinally to the "first" starting position indicated in Figs. 9 and 16. The compressed air throttle valve 17 is then opened.

60 65 In this position certain cam bumps on the

cam shaft 8 are so located relatively to the lifters that the compressed air valve will be opened, whereby compressed air will be admitted to the cylinders, causing the engine to turn in a forward direction. In this position of the cam shaft two cam bumps will successively engage the compressed air valve lifter 24, so as to admit compressed air on each down stroke of the piston, thus securing what is termed a "two-cycle" operation. 70 At the same time the valve lifter 25 for the exhaust valve 6 will be operated on each up stroke of the piston to allow the air in the cylinder to escape. In this first starting position there are no cam bumps so positioned as to operate the valve lifters 22 and 23, hence the atmospheric air intake valve and the fuel feed valve will remain motionless. When the engine has been speeded up sufficiently under the "two-cycle" operation of compressed air, the cam shaft 8 is shifted to a "second" starting position, indicated in Figs. 8 and 15. In this position the bumps on the cam shaft will serve to operate the compressed air valve lifter 24 only on every other down stroke of the piston, whereas the exhaust valve lifter will still be operated as before to open the exhaust valve on each up stroke of the piston. It will also be observed that in this "second" starting position another cam bump is brought into action to operate the lifter for the atmospheric air valve 4, which is now opened on each four-cycle "suction" stroke. In these two views, Figs. 8 and 15, the fuel valve 7 is still motionless. The cam shaft is maintained in this "second" starting position for only a brief period, an important purpose being to release, on the regular four-cycle compression stroke, the compressed air that would otherwise be retained in that cylinder from a previous "two-cycle" compressed air power stroke. If this were not done an excessive compression might occur in that particular cylinder on the up stroke sufficient to materially retard the rotative effort of the engine. 100

105 From the so called "second" starting position, the cam shaft 8 is shifted from the position shown in Fig. 8 to that shown in Figs. 7 and 14. In this latter position the bumps on the cam shaft are so arranged that they will operate all of the valve lifters 22, 23, 24 and 25 in such an order that the engine will operate normally as a "four-cycle" engine, atmospheric air being admitted on the suction stroke; that air being compressed on the compression stroke; fuel being forced in and ignited at or about the top of the compression stroke to furnish power during the next down stroke; the exhaust valve being opened on the next up stroke to permit the escape of burnt gases. 115

120 125 I have thus described how the engine is started in a forward direction from the

"neutral" position, this being accomplished by shifting the cam shaft longitudinally in one direction away from said neutral position thereof. To start the engine in a reverse direction the cam shaft is shifted in an opposite direction, there being a corresponding set of cam bumps on the cam shaft coacting with the several valve lifters at the proper time to cause the engine to rotate in a reverse direction.

It will be observed that whenever the throttle valve 17 is open the compressed air valve lifters 24 will be in position to operate the compressed air valves 5 so that, in the event the working pressure in the working cylinders 2 falls below that of the compressed air, said compressed air will then flow into the cylinder to prevent stalling and to assist in maintaining rotative effort. This is very advantageous, particularly in starting up the engine under a heavy load when cold. Manifestly, when the engine has been warmed up and is operating with normal efficiency, the throttle valve 17 may be closed.

It should be understood that the means for operating the various valves may be varied at will, so long as such means are capable of operating the valves in such order as to cause the engine to function as above described.

It will also be understood that, so far as concerns the construction of the various parts of the engine, the same may be modified in a variety of ways, so long as the aforesaid functioning is not interfered with.

From the foregoing it will be seen that the improvements relate not only to the mechanical construction described, but to the method employed in starting the engine.

What I claim is:

1. In an internal combustion engine of the four cycle high compression fuel burning type, a cylinder, a piston therein, an atmospheric air intake valve, a compressed air inlet valve, an exhaust valve and a fuel feed valve for said cylinder, valve controlling means to cause, when the same is in one position, the compressed air valve to be held open and admit compressed air to said cylinder on each down stroke of the piston and to cause the exhaust valve to be held open on each up stroke of the piston; and when in another position to cause the compressed air inlet valve to be held open and admit compressed air to said cylinder on each alternate down stroke of the piston, and to cause the atmospheric air intake valve to be held open on each intermediate down stroke of the piston, and to cause the exhaust valve to be held open on each up stroke of the piston; and when in another position to cause the atmospheric valve to be held open on one down stroke, to cause the fuel feed valve to be opened at about the top of the next up

stroke, to cause the atmospheric air intake valve and the exhaust valve to remain closed during the greater part of the next down stroke, and to cause the exhaust valve to be held open on the next up stroke.

2. In an internal combustion engine of the four cycle high compression fuel burning type, a cylinder, a piston therein, an atmospheric air intake valve, a compressed air inlet valve, an exhaust valve and a fuel feed valve for said cylinder, valve controlling means to cause, when the same is in one position, the compressed air valve to be held open and admit compressed air to said cylinder on each down stroke of the piston and to cause the exhaust valve to be held open on each up stroke of the piston; and when in another position to cause the compressed air inlet valve to be held open and admit compressed air to said cylinder on each alternate down stroke of the piston, and to cause the atmospheric air intake valve to be held open on each intermediate down stroke of the piston, and to cause the exhaust valve to be held open on each up stroke of the piston; and when in another position to cause the atmospheric valve to be held open on one down stroke, to cause the fuel feed valve to be opened at about the top of the next up stroke, to cause the atmospheric air inlet valve and exhaust valve to remain closed during the greater part of the next down stroke, and to cause the exhaust valve to be held open on the next up stroke, provided with compressed air operated means to normally hold the compressed air valve closed excepting when opened by said mechanical valve operating means, and with means provided for shutting off said compressed air.

3. In a fuel burning engine of the Diesel type, a plurality of cylinders, valves in one of said cylinders for atmospheric air admission, for exhaust, for fuel feed, and for admission of compressed air, means to control said valves whereby under one condition said cylinder will be operated by compressed air on the two-cycle principle, and under a second condition will be operated partly on the two-cycle and partly on the four-cycle principle, and under a third condition will be operated wholly on the four-cycle principle.

4. A reciprocating internal combustion engine of the four-cycle high compression fuel burning type, comprising first, means for introducing compressed air into the engine cylinder on each down stroke of the piston therein, and for opening said cylinder to atmosphere on each up stroke thereof; second, means for introducing compressed air into the cylinder on every alternate down stroke of the piston therein and for opening the same to atmosphere on each intermediate down stroke, while still continuing to open the cylinder to atmosphere on

each up stroke of the piston; and, third, will generate pressure against the piston to force it down on its next stroke, and for then opening said cylinder to atmosphere ¹⁰ whereby on the next up stroke of said piston the gases in said cylinder will be expelled.

BENJAMIN C. SMITH.
